CLAIM

The ornamental design for a handle for a multifunction tool, as shown and described.

DESCRIPTION

FIG. 1 is a front elevational view of a handle for a multifunction tool showing our new design;

FIG. 2 is a rear elevational view thereof;

FIG. 3 is a top view thereof;

FIG. 4 is a bottom view thereof;

FIG. 5 is a left side view thereof; and

FIG. 6 is a right side view thereof;

FIG. 7 is a front elevational view of a handle for a multifunction tool shown in an alternate configuration;

FIG. 8 is a rear elevational view thereof;

FIG. 9 is a top view thereof;

FIG. 10 is a bottom view thereof;

FIG. 11 is a left side view thereof; and,

FIG. 12 is a right side view thereof.

The broken lines represent unclaimed subject matter, and form no part of the claimed design.
